C. OTTO

PROCESS FOR DIRECTLY PRODUCING AMMONIA

Filed Aug. 15, 1927

UNITED STATES PATENT OFFICE.

CARL OTTO, OF ESSEN-RUHR, GERMANY.

PROCESS FOR DIRECTLY PRODUCING AMMONIA.

Application filed August 15, 1927, Serial No. 212,954, and in Germany August 9, 1926.

As is well-known, very high yields of distillation gases are obtained with the modern coal-distilling ovens. In obtaining these yields comparatively high coking temperatures are employed. The distillation gases produced are therefore very hot. The formation of the desired mobile high-grade tar in the hydraulic main is obtained by intensely irrigating the main by water or tar. With the so-called indirect or half-direct ammonia producing processes, in which the production of the ammonia takes place by cooling and washing the distillation gases by gas water, the treatment of the gases in the hydraulic main is not difficult because sufficient quantities of cooled gas water are at disposal for the irrigation of the hydraulic main. More unfavorable conditions, however, prevail with the so-called direct processes, as in these latter the formation of gas water is avoided as much as possible and the ammonia is obtained almost exclusively by directly washing the distillation gases by sulphuric acid. In the latter processes, there is but little gas water at disposal for the irrigation of the hydraulic main because this water must be used in circulation, and consequently is enriched during the circulation more and more with salts (ammonium chloride). The tar is thus considerably thickened and its treatment in the tar distillation is rendered very difficult. Now the invention has for its object to eliminate this drawback. To this end, the invention substantially consists in a combination of the known irrigating device for the hydraulic main with a special cooling installation for the gas and the condensate.

In order to allow of the invention to be more easily understood, a preferred embodiment of an installation adapted to carry out the present method, is diagrammatically illustrated by way of example in the drawing which accompanies and forms part of this specification.

Referring now to this drawing, *a* denotes the hydraulic main to which the distillation gases are supplied. These gases are led to cooler *d* through a pipe *b*, having a branch pipe *c*. From cooler *d* the gases pass through pipe *e* to a tar extractor *f* and further through pipe *g* into a saturator *h*. Through a pipe connected to an outlet socket *i*, the gas is led away from the saturator *h*, to other apparatus (not shown) for further recovery of byproducts, such as benzols.

The cooling liquid required for cooling the

gases in the hydraulic main *a* and in the vertical section of pipe *b* is taken from a tank *k*, into which the branch pipe *c* opens. The liquid flows through a pipe *m* to a pump *n* and is forced by the latter through a pipe *o* and supplied through branch pipe *p* and nozzle *q* into the hydraulic main *a* spraying it into the main, thus replacing the portion of the liquid evaporated therein and, on the other hand through pipe *o'* and nozzle *r* into the vertical section of pipe *b*, so as to irrigate the gases before reaching the cooler. The tarry condensate depositing in the hydraulic main *a* flows through pipes *b* and *c* into the tar receptacle *k*. The gas flowing through pipe *b* comes into contact with the irrigating liquid supplied by nozzle *r* to the vertical section of pipe *b* before entering the cooler *d*. Fresh condensate is thereby produced in the cooler *d* which is collected in the lower portion of cooler *d*, is there cooled separately and supplied again to receptacle *k* through a pipe *s*.

Owing to the different specific gravities of the constituents of the condensate, a first separation of the latter into tar and ammonia water takes place in the receptacle *k*. The ammonia water is led off through the above-mentioned pipe *m*, whilst the deposited tar is taken away through a pipe *t* into a second separating vessel *u*. As the liquids come completely to rest in vessel *u* owing to the latter being of sufficiently large dimensions, a complete separation of tar and ammonia water takes place therein. The heavy tar, depositing on the bottom, is withdrawn through a pipe *v*. The ammonia water, collects above the tar, and is taken off through a pipe *w*. Both substances are then led to another part 95 of the plant to be further utilized.

What I claim and desire to secure by Letters Patent, is:—

1. The steps in the described process for treating the distillation gases of coal gas producing furnaces for directly producing ammonia, which consist in feeding the distillation gases to a gas cooler, cooling them in the gas cooler so as to obtain a quantity of fresh condensate, feeding one part of the condensate to the hydraulic main, thus replacing the portion of the liquid evaporated therein, feeding another part of the condensate to the pipe leading to the cooler, so as to irrigate the gases, and returning the condensate to the cooler with a fresh supply of gas.

2. The steps in the described process for treating the distillation gases of coal gas producing furnaces for directly producing ammonia, which consist in feeding the distillation gases to a gas cooler, recovering tar from the distillation gases while the gases are fed to the gas cooler, cooling the gases in the cooler so as to obtain a quantity of fresh condensate, feeding one part of the condensate

to the hydraulic main, thus replacing the portion of the liquid evaporated therein, feeding another part of the condensate to the pipe leading to the cooler, and returning the condensate to the cooler with a fresh supply of gas.

In testimony whereof, I have signed my name to this specification.

CARL OTTO.
